UNITED STATES PATENT OFFICE.

CHARLES H. HORTON, OF WELLINGTON, OHIO.

BRICK-MACHINE.

SPECIFICATION forming part of Letters Patent No. 415,270, dated November 19, 1889.

Application filed July 13, 1889. Serial No. 317,428. (No model.)

To all whom it may concern:

Be it known that I, CHARLES H. HORTON, of Wellington, in the county of Lorain and State of Ohio, have invented certain new and useful Improvements in Brick-Machines; and I do hereby declare the following to be a full, clear, and exact description of the invention, such as will enable others skilled in the art to which it appertains to make and use the same.

My invention relates to an improvement in brick-machines.

The object is to provide a machine for molding brick; and it consists in a mud-press geared in such a manner that its wear is very slight, and leaking of mud to the outside of the machine is absolutely prevented, this press being employed in connection with mechanism for regulating the stroke of the press and also mechanism for properly tempering the material for making the bricks, filling the molds to form the bricks, and means for removing the molds at predetermined intervals.

With this end in view my invention further consists of certain novel features of construction and combination of parts, as will be hereinafter described, and pointed out in the claims.

In the accompanying drawings, Figures 1 and 2 are right and left side elevations of the machine. Fig. 3 is an end view of the mud-press. Fig. 4 is a plan view of the latter. Fig. 5 is a detached view of the cam-yoke. Fig. 6 is a view of the mold-press, and Figs. 7 and 8 are detached views of parts. Fig. 9 is a front elevation, parts being broken away.

A represents the main pugging-box. The latter is of the usual construction, and the pugging-shaft 1 is journaled vertically therein and furnished with the grinders 2 2 at short intervals throughout its length. The mud-press 3 is located at the lower end of the pugging-box and to one side of the pugging-shaft, as shown. The blade of this press is flat on the face 4, which presses the mud, and preferably oval or rounded on the opposite or upper face 5. The stuffing-box is made to prevent mud from working its way into the box or its bearings of the press, and it is constructed as follows: An annular chamber 6, about one and a quarter inch deep by seven-

eighths wide, is made around the shaft 7, and in the bottom of this chamber is placed an elastic packing, and on top of this packing is placed a metal ring 9, and against the latter is pressed the follower 10, which is held securely in place by bolts or similar means 11, passing through ears 12 12, as shown in Fig. 2. When it is necessary to crowd the follower, 60 the main boxes are loosened slightly, (they being made in halves,) and after drawing up the follower by means of the bolts extending through the ears the main box is again tightened. The metallic ring forms a tight joint 65 against the end of the follower, so as to entirely exclude the mud from the bearing, which is important in this style of press.

When the press is down, the mud, being worked and ground by the grinders, fills the 70 space left by the press going down, and as the press comes back the mud rolls over the top of the press in front and in position to be pressed through the dies 13 into the molds 14 14 below.

In order to work different clays, and as it is impossible to temper different clays alike, it is necessary that the mud-press 3 should be entirely under the control of the operator, so that its stroke may be regulated. The full 80 stroke of the press is about a quarter-revolution, and the power is exerted from one end of the machine by means of the following mechanism: A crank 15 is fastened to one end of the shaft on which the mud-press is 85 mounted, and an extensible pitman 16 connects this crank with a crank-disk 17, which is fastened to the end of a shaft on which is a pinion (not shown) driven by a bevel gear-wheel 18, affixed to the main pugging-shaft 1, 90 and the latter is generally driven by horse-power attached to a lever (not shown) fastened to the socket 18^a, or it may be driven by power communicated by belt or rods.

To return to the extensible pitman, it 95 should be explained that it is so made in order to control the movement of the press, as different lengths of strokes are required with clay of different quality and consistency. The pitman is slotted at its lower end and arranged to allow the toothed piece 19 to slide therein the full length of the stroke, unless prevented by the dog 20, which is pivoted to the pitman. At each revolution of the crank-

disk 17 the pitman is drawn upward until its end engages the end of the toothed piece, when the latter is carried along with it. The dog 20 naturally drops by gravity into each 5 notch until it finally drops into the top notch. Here it is retained, and upon the downstroke the crank would carry the mud-press the full length of its stroke, thus pressing the mud to the utmost capacity; but to regulate this 10 stroke and lessen the pressure I arrange an escape-slide 21 (somewhat longer than the stroke) on the side of the machine. This slide is slotted and held loosely on the side of the machine by headed bolts 22, so that it will 15 work easily up and down with the movement of the lever 23, which is connected with it by a pin 24, the opposite end of the lever being held to the machine by a link 25. A series of notches are arranged to engage the lever 20 and hold it in position. Now it is obvious if the lever is placed in the upper notch the pin 26 in the dog, which projects toward the machine, would not pass out far enough in 25 its upward movement to ride over the escape-slide 21. So, instead, the dog will drop into each notch until at last it will remain in the top one, and therefore carry the press the full length of its stroke upon the return movement of the pitman. If, though, the lever 23 30 be depressed, say, to the third notch, the pin would ride over the slide and be lifted from the notched piece, and it would not return to it until three notches had been passed. It would then engage one of the lower notches 35 and limit the length of the stroke correspondingly.

If it is desired to stop the press, the operator depresses the lever to the lowest notch, drawing the escape-slide down until the pin, 40 on the dog travels the entire length of its stroke on the escape-slide out of contact with the notched piece.

In Fig. 7 the tenoned end of the toothed piece 19 is shown, the latter being arranged 45 with side pieces to guide it on the straps of pitman 16.

An opening 27 is formed in the side of the machine and through it the molds are slid, and the following mechanism is devised to 50 drive the mold-press at the proper periods in order to force forward the molds and effect a quick return, so that the press may remain still after being drawn back half of the time in order to allow the man feeding the molds 55 to the machine time to slide in the molds without endangering himself or getting his mold caught.

The mold-press is shown detached in Fig. 6. It consists of two side pieces 28 28, which 60 are slotted to receive bolts or cap-screws 29 29 in order to permit them to slide back and forth. These cap-screws 29 29 fasten into the portion that forms the front of the press, and two set-screws 30 30 prevent the cap-screws or bolts from slipping in the slots 65 when the pressure comes against the front end of the press, as it always does. The front end

is supported at its middle by a wheel or roller 31, which travels in a suitable track in mold-rack 32. The rear end of this press is carried by arms 33 33, which are fastened to and swing by shaft 34, which is driven by crank 35 and that by extensible pitman-rod 36, which is connected by cam-yoke 37, said cam being driven by disk 17. This cam-yoke is driven by two 70 anti-friction rollers 39 and 40. One of these rollers is placed on the shaft which carries the crank-disk and the other one on the back side of this disk the proper distance away from the other roller to produce the required 75 amount of travel. Said roller 40 on the disk, in other words, is placed so as to push out the mold at the time the mud-press is down, and in order to make it earlier or later, according to the material to be worked, other holes may 80 be arranged in the disk, so that the pin on which the roller 40 is mounted may be changed forward or backward at the will of the operator to regulate the stroke.

The handle 41 on the left side of the machine is for the purpose of raising or lowering the mold-rack to correspond to the height of the molds, there being two eccentrics, (one on each side,) so that by rocking the handle the mold-rack is correspondingly raised or lowered and is fastened in position by bolt 42 in the slotted casting 43.

The doors 44 44 are hinged to the front of the machine and held down by springs 45 45 in the usual manner, so that when a stone or other hard substance gets into the molds the said doors are pushed open by it as the mold passes out.

The operation has been from time to time explained, so that it would be unnecessary to enter into a detailed description here; and in conclusion I may say that various slight changes might be resorted to in the form and arrangement of the several parts described without departing from the spirit and scope 105 of my invention, and hence I do not wish to limit myself to the particular construction herein set forth; but,

Having fully described my invention, what I claim as new, and desire to secure by Letters 115 Patent, is—

1. The combination, with a pugging-box and a press, of a two-part pitman, the two sections having a sliding engagement, a locking device attached to one section of the pitman 120 and engaging the other section for locking them together, and a trip or abutment for actuating the locking device to disconnect the sections, substantially as set forth.

2. The combination, with a pugging-box and a press, of a two-part pitman, the two sections having a sliding engagement, a locking device attached to one section of the pitman 125 and engaging the other section, and a trip or abutment for withdrawing the locking device 130 and holding same during a portion of the stroke of the pitman, substantially as set forth.

3. The combination, with a pugging-box, a

pugging-shaft, and grinders on the latter, of a rocking mud-press, gearing for operating the shaft, an extensible pitman connecting the pitman with the mud-press, and a hand-lever 5 for regulating the length of throw of the pitman and the stroke of the press, substantially as set forth.

4. The combination, with a pugging-shaft and grinders on the latter, of a rocking mud-press, a crank thereon, a crank-disk, an extensible pitman connecting the disk and crank, a dog on the pitman, an escape-slide, and a hand-lever for changing the position of the latter to regulate the stroke of the press, substantially as set forth.

5. A mud-press having a blade thereon, an annular chamber in the end, and packing-rings and follower for forming a mud and water tight bearing, substantially as set forth.

20 6. A mud-press having a blade flat on one side and rounded on the other, an annular chamber in the end, an elastic and a metal packing-ring, a follower adapted to enter the chamber, and means for tightening or 25 loosening this joint, substantially as set forth.

7. The combination, with a pugging-box, a shaft, and grinders, of a mud-press, a crank thereon, gear-wheels, crank-disk, a pitman having a toothed piece extending therein, a pivoted dog having a pin therein, an escape-slide, and a hand-lever for changing the position of the latter to regulate the stroke of the press, substantially as set forth.

8. The combination, with a pugging-box, 30 pugging-shaft, grinders, and mud-press, of 35 molds, extensible mold-press mounted on a roller at its forward end, a pitman, a cam-yoke thereon, and rollers therein for regulating the throw of the pitman and the stroke of the mold-press.

In testimony whereof I have signed this specification in the presence of two subscribing witnesses.
